UNITED STATES PATENT OFFICE.

PAUL I. BURKS, OF LOUISVILLE, KENTUCKY.

EXPRESSION DEVICE FOR PNEUMATIC PIANO-PLAYERS.

1,219,243.

Specification of Letters Patent. Patented Mar. 13, 1917.

Application filed November 30, 1915. Serial No. 64,244.

To all whom it may concern:

Be it known that I, PAUL I. BURKS, a citizen of the United States, residing at Louisville, in the county of Jefferson and State of Kentucky, have invented new and useful Improvements in Expression Devices for Pneumatic Piano-Players, of which the following is a specification.

This invention relates to an expression device for use in pneumatic piano players, and has for its main object to provide a valve control mechanism wherein the action is direct and the usual auxiliary valves are done away with.

It is an object of this invention to provide a controlling valve which is of such structure that it may be used with a second like valve, and the two when thus coupled counter-balance each other and act upon each other as auxiliary valves.

It is another object of the invention to provide an operating valve which is coupled to a similar valve so that when only one of the valves is opened the second valve is automatically closed, and vice versa.

It is a further purpose of this invention to provide a pouch or diaphragm, for controlling the main valve, with a bleed hole which is automatically cleaned or prevented from clogging up by the fluctuations of the pouch or diaphragm. This feature of the invention embraces the formation of one or more bleed holes directly in the pouch or diaphragm, in the flexible portion thereof, so that as the diaphragm or pouch is distended or collapsed the material through which the bleed holes are formed is flexed or bent so as to dislodge any dust, lint, or the like, which may collect about and over the bleed opening, and thus keep the same open and cleared at all times.

While the present invention is particularly adapted for use with expression devices in automatic pneumatic piano players, it will be understood that this counter-balancing valve feature may be used in connection with other mechanism which is adapted to be controlled or operated by the collapsing and distending of pneumatics, and wherein the structure may be simplified by the counter-balancing valves of this invention.

In the accompanying drawings one embodiment of the invention is shown, the same being described in detail as follows, and wherein in various other objects and advantages will be more particularly pointed out.

In the drawings,—

Figure 1 is a perspective view of the improved expression device, its application to the tracker bar being shown diagrammatically, and the valve chest being disclosed in section to show the coöperating parts of the mechanism.

Fig. 2 is a horizontal sectional view taken through the valve chest immediately beneath the cap plate thereof.

Fig. 3 is a horizontal sectional view taken through the valve chest taken immediately beneath the valve supporting plate, and showing the pouches with the improved bleed holes therein.

Fig. 4 is a transverse section taken through the valve chest and the parts therein on the line 4—4 of Fig. 2.

Fig. 5 is a longitudinal section through the valve chest and its parts taken centrally through the row of front valves.

Referring to the drawings, wherein like parts are designated by similar characters of reference throughout the several views, and particularly to Fig. 1, 10 designates the base plate or support of the valve chest wherein the improved valves and mechanism of this invention are carried.

This base plate 10 has mounted upon it a valve supporting and guiding plate 11 covered by a cap plate 12. The three plates are assembled one upon the other as shown in Fig. 1, and a suitable packing 13 is interposed between the adjacent upper and lower edges of the plates to form an air tight seal between them.

The base plate 10 is provided with a plurality of depressions or pockets 14 arranged preferably in longitudinal rows and in offset or staggered relation, as shown in Figs. 1, 2 and 3. Each pocket 14 has, leading from the forward side thereof, an air vent passage 15 extending in the base plate 10 to the front of the same, and terminating in a connecting nipple 16 which projects forwardly from the valve chest. As shown in the drawings, there are two rows of these pockets 14, three to each row, and from the forward row the nipples 16 project, while from the rear row the nipples 16 project.

Each of the pockets 14 is provided with a covering diaphragm or pouch 17 adapted to extend down into the pocket 14, and provided with a wear button or plate 18 at its middle portion. The diaphragms 17 may be made in one piece which is suitably

stretched over the entire upper face of the base plate 10 and thus over the pockets 14, or the diaphragms may be made in any other suitable or convenient manner.

5 The base plate 10 is also provided in its upper side, and adjacent its rear edge, with an exhaust opening 19 connected to an exhaust pump or chamber, and which terminates in a passage 20 extending forwardly 10 through the base plate to a point preferably between the forward and rear rows of diaphragms, where the passage 20 opens upwardly, as shown at 21. Fitted upon the top of the base plate 10 and over the diaphragms 17 is the valve supporting and guiding plate 11 which is of a depth sufficient to cover all of the diaphragms, and to clear the exhaust opening 19, so that the latter may be suitably connected with the exhaust pump 15 or chamber. The lower face of the plate 11 is recessed at its middle portion to provide an exhaust chamber 23 within the valve chest, the exhaust chamber 23 extending over all of the diaphragms 17 so as to position the 20 exhaust chamber 23 at the upper sides of the diaphragms and the pockets 14 beneath the diaphragms.

Each diaphragm 17 is provided in its flexible portion, between the wear button 18 and 30 the edge of the pocket 14, with one or more openings 24 constituting bleed holes for establishing communication between the pockets 14 and the exhaust chamber 23.

The valve supporting and guiding plate 35 11 is provided in its upper face with a plurality of valve chambers 25. The valve chambers 25 correspond in number to the number of diaphragms 17, and are arranged in vertical alignment therewith, and communicate with the chamber 23 by means of 40 passages 26 which are formed in the plate 11 in the bottoms of the valve chambers 25. In each chamber 25 there is mounted a disk valve 27, the latter normally resting upon 45 a valve seat 28 in the bottom of the chamber 25 about the upper end of the passage 26, and having a depending stem 29 which passes loosely through the passage 26 and bears upon the wear button 18 of the diaphragm 50 immediately below the valve. It will be noted particularly from Figs. 4 and 5 that the stems 26 are of less diameter than the diameter of the openings or passages 26 so that when the valves 27 are raised from 55 the seats 28, free communication is established between the exhaust chambers 23 and the valve chambers 25.

The valve chambers 25 are all closed by a single cap plate 12, the latter extending 60 entirely over the top of the valve supporting and guiding plate 11 and thus closing in all of the valves 27. The cap plate 12 is provided upon its upper face with a plurality of connecting blocks 30 which are arranged 65 in rows, one immediately over each valve 27.

The connecting blocks and the cap plate 12 are provided with vertical passages 31 leading directly upward from the valve chambers 25 and opening laterally through the blocks 30 to establish communication, when 70 the valves are seated, between the valve chamber 25 and the atmosphere. The blocks 30 and the cap plate 12 are also provided with relatively small openings or passages 32 which are branched within the connecting blocks 30, one branch terminating in the nipple 33 while the opposite branch terminates in the nipple 34. The nipples 34 project forwardly from the connecting blocks 30 while the nipples 33 preferably extend upwardly therefrom. 80

The valve supporting and guiding plate 11 is provided in its forward and rear edges with openings 35 adapted to receive nipples 36, as shown in Fig. 1 of the drawings, and to which are attached flexible tubes 37 leading to the opposed pneumatics 38 and 39. Springs 40 are mounted on the pneumatics to expand or distend the same when the tubes 37 and the valve chamber 25 are opened 90 to the atmosphere, by the seating of the valves 27. The movable leaves of the pneumatics are provided with connecting rods 41 or the like which lead to the valves or other devices to be actuated by the pneumatics 38 95 and 39.

The valves and their parts, as herein disclosed, are arranged in pairs, and, as shown, the connecting block over the first valve of the first row is connected to the first valve of the rear row by means of the tube 43 and the connecting block over the first valve of the rear row is connected to the first valve of the front row, by means of the tube 42. The tube 42 leads from the nipple 34 of the first 100 rear valve to the nipple 16 of the pocket 14 of the first valve of the front row. The tube 43 is crossed with the tube 42, and extends from the nipple 34 of the first valve of the front row to the nipples 16^a of the pocket 14 of the first valve of the rear row. It is thus seen that the connection is such that the connecting block 30 of each one of the pair of interconnected valves communicates with the pocket 14 beneath the diaphragm 17 of the opposite one of the same pair of valves. In Fig. 1 of the drawings one pair of valves is shown diagrammatically connected to the pneumatics and the tracker bar, while the other parts are merely shown for the purpose of illustrating that any number of pairs of these interbalancing valves may be employed to control or operate as many expression or other devices as is found desirable. 110

The nipple 33 of one of the connecting blocks 30 is connected by tube 44 to the tracker bar 45, the same having an opening 44^a which communicates with the tube 44. The opposite connecting block 30 of the same 120 130

pair of valves is connected by tube 46 to the tracker bar 45 and has communication with the tracker opening 46^a, for admitting atmospheric air to the tube 46 when the perforations 44^b and 46^b in the note sheet 47 register with the tracker openings 44^a and 46^a.

In operation, when one of the perforations 44^b of the note sheet 47 is brought into register with the tracker bar opening 44^a, air is admitted to the tube 44 and through the connecting block 30 of the forward valve, as shown in Fig. 1, into the tube 43, which leads to the pocket 14 of the rear valve by way of the duct 15. Air being thus admitted to the pocket 14, and the exhaust chamber 23 being above the diaphragm or pouch 17, raises the latter momentarily to unseat the valve 27 and establish communication between the exhaust chamber 23 and the pneumatic 38, through the tube 37, nipple 36, and duct 35. When the valve 27 is thus raised its upper face seats against the cap plate 12, closes the atmospheric opening 31 to the valve chamber, and also closes the passage 32 which leads down through the connecting block 30 from the tracker tube 46. As the tracker tube 46 is closed, and as the passage 32 is closed by the valve 27, the tube 42 is placed under vacuum by reason of its connection with the nipple 16, which leads through channel 15 into the pocket 14 of the front valve, which pocket 14 is exhausted of air through the bleed hole 24 in the diaphragm 17. Thus the diaphragm 17 of the front valve is permitted to fall and the valve 27 above the diaphragm is permitted to seat.

The seating of the valve 27 closes communication between the pneumatic 39, connected to the front valve chamber 25 by means of the nipple 36 and tube 37, as shown in Fig. 1, whereby the pneumatic 39 is opened to the atmosphere through the passage 31, and is thus permitted to expand. At the same time, the valve 27 uncovers the passage 31 to the atmosphere, and also opens the relatively small passage 32 which leads to the cross tube 43 to admit air to the pocket 14 of the rear diaphragm 17. This permits the rear diaphragm to remain raised, as shown in Fig. 1, and to thus hold the rear valve 27 upwardly from its seat 28. The parts remain in this position until the perforation 46^b of the note sheet is brought into registry with the opening 46^a in the tracker bar. When this occurs, air is admitted to the tube 46, through connecting block 30, into the cross tube 42 and into the front pocket 14. Air being thus admitted beneath the diaphragm, the suction in the chamber 23 lifts the diaphragm and the valve 27 therewith so as to effect the seating of the rear valve and the consequent retaining of the front valve in raised position.

It is thus seen that I have provided a pair

of main valves which are so connected together that it is not necessary to provide auxiliary valves, as the main valves themselves act for each other as auxiliary valves. The pneumatics 38 and 39 may be connected to expression devices, slide or other form of valves, or to any other mechanical devices which are adapted to be actuated or controlled from a note sheet.

I claim:—

1. In pneumatic mechanism, a pair of valves, a pouch for each valve, an exhaust chamber communicating with one side of said pouches, a pocket communicating with the opposite side of each pouch, and a duct leading from each pocket and adapted to be opened and closed to the atmosphere by the valve of the opposite pocket. 70

2. In pneumatic mechanism, a pair of valves, a pouch beneath each valve to actuate the same, and means controllable by each valve for actuating the pouch beneath the other valve. 85

3. In pneumatic mechanism, a pair of valves, means for actuating the valves, and a connection between said actuating means of one valve and the opposite valve for controlling the operation of the first valve. 90

4. In pneumatic mechanism, a pair of valves, means for unseating one of the valves, means between said valve and the second valve for holding said second valve to its seat, and a connection between the second valve and the first valve whereby to maintain the first valve in unseated position. 100

5. In pneumatic mechanism, a pair of valves, means to initially open one of the valves, a connection between said valves adapted to close one valve upon the opening of the opposite valve, and means between the opposite valve and the first valve to retain the first valve open when the second valve is closed. 105

6. In pneumatic mechanism, a valve chest having an exhaust chamber therein, a pair of pneumatics connected to the exhaust chamber, a valve for each pneumatic controlling communication between the separate pneumatics and the exhaust chamber, means for initially opening one of the valves whereby to exhaust one of the pneumatics, a connection between said valves adapted to seat the second valve upon the initial opening of the first valve, and means controllable by the second valve adapted to retain said first valve open when said second valve is seated. 115

7. In pneumatic mechanism, a valve chest, a pair of valves mounted in the valve chest, an exhaust chamber in the valve chest, ducts leading from the valve chest past said valves and adapted to be controlled thereby, tracker tubes leading from the valve chest and being controlled by said valves, a pouch beneath each valve for actuating the same, 130

said pouches communicating at one side with said exhaust chamber, a pocket at the opposite side of each pouch, and ducts leading from the pouches to said valves whereby 5 upon the opening of one valve the pocket of the opposite valve is closed to collapse the opposite pouch and seat the opposite valve, and whereby the seating of the opposite valve opens the pocket of the first valve to 10 retain the latter in open position.

8. In pneumatic mechanism, a valve chest having a pair of pockets therein and ducts leading outwardly from the pockets, a pouch over each pocket, an exhaust chamber 15 above said pouches, a valve above each pouch adapted to be operated thereby, a valve chamber about each valve communicating with the exhaust chamber and with the outside atmosphere, a pneumatic communicating with each valve chamber adapted to be alternately opened to the exhaust chamber and to the atmosphere, and a duct leading 20 from each valve chamber to the pocket of the opposite valve whereby the operation of 25 one valve controls the operation of the opposite valve.

9. In pneumatic mechanism, a pair of pneumatics, a pair of valves adapted to control the operation of the pneumatics, and 30 means connecting the valves whereby each valve operates upon the other valve as an auxiliary valve.

10. In pneumatic mechanism, a pair of valves, a pneumatic for each valve, and 35 means connecting the valves for equalizing the same.

11. In pneumatic mechanism, a pair of valves, a pneumatic connected to each valve, means for initially opening one of the valves, 40 means for seating the opposite valve upon the opening of the first valve, and other means between the valves adapted to maintain the first valve open when the second valve is seated.

45 12. In pneumatic mechanism, a valve

chest, a pair of connected valves in the valve chest, a tracker tube leading from each valve and adapted to initially actuate the valve upon the opening of the tube, and means controlled by the valves for maintaining 50 the tracker tube of the second valve closed whereby to maintain the first valve open.

13. In pneumatic mechanism, a valve chest having pockets in the lower part thereof, a pouch covering each pocket, a duct 55 leading forwardly from each pocket, an exhaust chamber above the pouches, valves in the top of the exhaust chamber having stems bearing upon said pouches, a pneumatic tube leading from each valve, an open tube leading 60 from each valve, a tracker tube leading from each valve, and a branch tube leading from each valve to the pocket of one of the other valves.

14. In pneumatic mechanism, a pair of 65 opposed pneumatics, an exhaust chamber connected to the pneumatics, a valve chamber between the exhaust chamber and each pneumatic, a valve in each valve chamber adapted when seated to close communication 70 between the exhaust chamber and the respective pneumatic, a pouch in communication with the exhaust chamber and arranged immediately beneath each valve, and tracker tubes leading into said valve chambers and 75 beneath said pouches, said valve chambers having openings through the sides thereof leading into the atmosphere and adapted, when the valves are seated, to open the pneumatics and the tracker tubes to the 80 atmosphere, said tracker tubes leading from the valve chamber of one valve to the pouch of the opposite valve.

In testimony whereof I have hereunto set my hand in presence of two subscribing witnesses.

PAUL I. BURKS.
